UNITED STATES PATENT OFFICE.

ANTONINE ULANYTZKY, OF COHOES, NEW YORK.

TORPEDO GUARD AND CATCHER.

1,257,154.

Specification of Letters Patent. Patented Feb. 19, 1918.

Application filed June 21, 1917. Serial No. 176,067.

To all whom it may concern:

Be it known that I, ANTONINE ULANYTZKY, a subject of the Emperor of Austria, residing at Cohoes, in the county of Albany and State of New York, have invented certain new and useful Improvements in Torpedo Guards and Catchers, of which the following is a specification.

This invention relates to torpedo guards 10 for warships and other vessels and has special reference to an electromagnetic torpedo guard and catcher.

One important object of the invention is to improve the general construction of devices of this character.

A second important object is to provide a device of this character wherein a torpedo approaching the vessel will be caught by electromagnetic means, the device also 20 having as an object to permit the torpedo being raised to the deck of the vessel by the catching means when it is caught.

A third important object is the provision of the improved arrangement of guard 25 which will check the speed of an approaching torpedo gradually so that upon its arrival at the electromagnetic means it will be seized magnetically without shock and consequent danger of explosion.

30 A fourth important object of the invention is the provision of an improved device of this character wherein the approaching torpedo will, in the act of being caught, close an electric circuit which will automatically operate the mechanism to raise the torpedo on to the deck of the vessel.

With the above and other objects in view, as will be hereinafter apparent the invention consists in general of certain novel details of construction and combinations of parts hereinafter fully described, illustrated 40 in the accompanying drawings, and specifically claimed.

In the accompanying drawing, like characters of reference indicate like parts in the several views, and:

Figure 1 is a transverse section through a portion of the hull of the vessel showing the apparatus in elevation.

50 Fig. 2 is a side elevation of a portion of the hull of the vessel with the apparatus in position.

Fig. 3 is a detail section on the line 3—3 of Fig. 1.

55 Fig. 4 is an enlarged detail view partly

in section and partly diagrammatic showing the arrangement of the circuit closer and electromagnet used herewith.

In the embodiment of the invention illustrated in the accompanying drawings there 60 is seen a portion of the hull of a vessel indicated in general at S. Mounted on this hull beneath the water line are brackets 10 and to each of these brackets is pivoted a curved outrigger 11 provided at its free 65 extremity with a link 12 to which is connected one end of a hoisting cable 13. This hoisting cable is led upward and inboard over a pulley over sheave 14 mounted on the davit 15. The remaining end of the 70 cable 13 is connected to the winding drum of a motor typically indicated at 16.

Mounted on the side of the hull above each of the brackets 10 is a second bracket 17 and each of the brackets 17 carries a 75 sheave 18 and depending from the extremity of the davit is a sheave 19, the sheaves 18 and 19 being connected by endless ropes 20. The sheave 19 is fixed on its shaft or axle and this shaft or axle furthermore carries 80 a pulley 21 which is connected by an endless rope or cable 22 with a pulley 23 at the base of the respective davit, the pulley 23 being provided with a handled crank 24 for the purpose of operating it. Connected to 85 each of the cables 20 is a link 25 and carried by the links 25 and 12 is a torpedo net 26 which is sufficiently slack when in torpedo catching position to take the curved form shown in Fig. 1, the curve being of course 90 substantially a catenary. Just above the water line behind each of the nets 26, which it will be observed each preferably forms a separate section, is an electromagnet having a core 27 and a winding 28 which is energized, when the device is in use, from any suitable source of power, the latter not being deemed necessary here to be shown. The core 27 carries on its outer end an elongated pole piece 29 the shape of which can best be 95 seen by reference to Fig. 2. Passing through each of these pole pieces is a yoke 30 carrying on its inner end an insulated contact member 31 and having its arms connected exteriorly of the pole piece 29 by a bar 32. 100 The contact 31 is so arranged that when the yoke is moved inward it will engage a second contact 33 as can be seen by reference to Fig. 4. The contact 31 is connected by a wire 34 with a suitable source of electric 105 power.

Fig. 3 is a detail section on the line 3—3 of Fig. 1. Fig. 4 is an enlarged detail view partly

energy here typically indicated by the battery 35. This battery is connected in multiple by wires 36 with the motors 16 of the respective net section. Moreover, the contact 33 is connected by wires 37 with the remaining brushes of the motors 16 so that when the contacts 31 and 33 close current will flow from the battery 35 through the motors and actuate these motors to draw up upon the cables 13. Moreover, if it be desired, an alarm bell or other suitable alarm as indicated at 38 may be interposed in a suitable place in the electric circuit so that when the contact is closed the alarm will indicate such closing.

In order to understand the operation of the device let it be supposed that the torpedo 39 approaches the ship S. The torpedo will strike that portion of the net which is nearly horizontal and will run up the curve of the net being, by this action, slowed down in speed so that as the end of the torpedo rises out of the water its momentum will have been practically checked. Owing to the torpedo forcing the net inward in its movement toward the ship the net will strike the bar 32 and close the circuit above-noted. At the same time the magnet, which is constantly energized when the device is in use, will hold the torpedo in its raised position so that it is prevented from sliding back off of the net. Now when the circuit is closed and the motor 16 operated the outriggers 11 will be triced up as indicated in dotted lines in Fig. 1. Then the crank 24 may be operated to draw the inner edge of the net upward above the ship's deck. Suitable tackle may then be connected to this inner edge and the edge drawn inboard so that the torpedo may be rolled out of the net onto the ship's deck without danger to the ship or injury to the torpedo.

Thus the torpedo is not only stopped from injuring the ship but is caught for future use against the enemy.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new, is:

1. A torpedo guard and catcher for ships including a net arranged in spaced relation to the side of a ship and having its lower edge portion extending outwardly away from the ship and its upper edge portion substantially vertical, and a magnet pro-

jecting from the side of the ship behind said upper edge portion.

2. A torpedo guard and catcher for ships including a net arranged in spaced relation to the side of a ship and having its lower edge portion extending outwardly away from the ship and its upper edge portion substantially vertical, and means to hoist the outer edge of said net and carry the same toward the side of the ship. 75

3. A torpedo guard and catcher for ships including a net arranged in spaced relation to the side of a ship and having its lower edge portion extending outwardly away from the ship and its upper edge portion substantially vertical, means to hoist the outer edge of said net and carry the same toward the side of the ship and motor means for said hoisting means arranged to operate automatically upon impact of a torpedo 85 against said net.

4. A torpedo guard and catcher for ships including a net arranged in spaced relation to the side of a ship and having its lower edge portion extending outwardly away 90 from the ship and its upper edge portion substantially vertical, means to hoist the outer edge of said net and carry the same toward the side of the ship, a normally open electric circuit including a circuit closer and 95 a motor for operating the hoisting means, and means to close the circuit closer upon impact of a torpedo against said net.

5. A torpedo guard and catcher for ships including a net arranged in spaced relation 100 to the side of a ship and having its lower edge portion extending outwardly away from the ship and its upper edge portion substantially vertical, means to hoist the outer edge of said net and carry the same 105 toward the side of the ship and other means to hoist the inner edge of said net.

6. A torpedo guard and catcher for ships including a net arranged in spaced relation to the side of a ship and having its lower 110 edge portion extending outwardly away from the ship and its upper edge portion substantially vertical, means to hoist the outer edge of said net and carry the same toward the side of the ship, motor means 115 for said hoisting means arranged to operate automatically upon impact of a torpedo against said net, and other means to hoist the inner edge of said net.

7. A torpedo guard and catcher for ships 120 including a net arranged in spaced relation to the side of a ship and having its lower edge portion extending outwardly away from the ship and its upper edge portion substantially vertical, means to hoist the 125 outer edge of said net and carry the same toward the side of the ship, a normally open electric circuit including a circuit closer and a motor for operating the hoisting means, and means to close the circuit closer upon 130

impact of a torpedo against said net, and other means to hoist the inner edge of said net.

8. A torpedo guard and catcher for ships including a net arranged in spaced relation to the side of a ship and having its lower edge portion extending outwardly away from the ship and its upper edge portion substantially vertical, means to hoist the outer edge of said net and carry the same toward the side of the ship, and a magnet projecting from the side of the ship behind said upper edge portion.

9. A torpedo guard and catcher for ships including a net arranged in spaced relation to the side of a ship and having its lower edge portion extending outwardly away from the ship and its upper edge portion substantially vertical, means to hoist the outer edge of said net and carry the same toward the side of the ship, motor means for said hoisting means arranged to operate automatically upon impact of a torpedo against said net, and a magnet projecting from the side of the ship behind said upper edge portion.

10. A torpedo guard and catcher for ships including a net arranged in spaced relation to the side of a ship and having its lower edge portion extending outwardly away from the ship and its upper edge portion substantially vertical, means to hoist the outer edge of said net and carry the same toward the side of the ship, a normally open electric circuit including a circuit closer and a motor for operating the hoisting means, means to close the circuit closer upon impact of a torpedo against said net, and a magnet projecting from the side of the ship behind said upper edge portion.

11. A torpedo guard and catcher for ships including a net arranged in spaced relation to the side of a ship and having its lower

edge portion extending outwardly away from the ship and its upper edge portion 45 substantially vertical, means to hoist the outer edge of said net and carry the same toward the side of the ship and other means to hoist the inner edge of said net, and a magnet projecting from the side of the ship 50 behind said upper edge portion.

12. A torpedo guard and catcher for ships including a net arranged in spaced relation to the side of a ship and having its lower edge portion extending outwardly away 55 from the ship and its upper edge portion substantially vertical, means to hoist the outer edge of said net and carry the same toward the side of the ship, motor means for said hoisting means arranged to operate 60 automatically upon impact of a torpedo against said net, other means to hoist the inner edge of said net, and a magnet projecting from the side of the ship behind said upper edge portion. 65

13. A torpedo guard and catcher for ships including a net arranged in spaced relation to the side of a ship and having its lower edge portion extending outwardly away from the ship and its upper edge portion 70 substantially vertical, means to hoist the outer edge of said net and carry the same toward the side of the ship, a normally open electric circuit including a circuit closer, a motor for operating the hoisting means, 75 means to close the circuit closer upon impact of a torpedo against said net, other means to hoist the inner edge of said net, and a magnet projecting from the side of the ship behind said upper edge portion. 80

In testimony whereof I affix my signature.
